UNITED STATES PATENT OFFICE.

WILLIAM N. PARKES, OF BROOKLYN, NEW YORK.

ZEYELET OR EMBROIDERY STITCHING MACHINE.

No. 875,614.

Specification of Letters Patent.

Patented Dec. 31, 1907.

Application filed May 28, 1903. Serial No. 158,812.

To all whom it may concern:

Be it known that I, WILLIAM N. PARKES, a citizen of the United States, residing in Brooklyn, county of Kings, and State of New York, have invented a new and useful Improvement in Eyelet or Embroidery Stitching Machines, of which the following is a description.

This invention relates to machines in which a relative lateral movement is produced between the needle and the work.

One of the main objects of the invention is to provide improved means for stitching an eyelet without turning the work.

It is also an object of the invention to provide means for automatically embroidering various ornamental designs, the stitches of which radiate completely around a common center.

With the above and other objects in view, which will be seen from the description and drawings, my invention consists in the parts, elements, and combinations hereinafter described and claimed.

Referring to the drawings: Figure 1 shows, in front elevation, so much of the machine as is deemed necessary to illustrate this view of my invention; Fig. 2 shows a rear elevation of the machine; Fig. 3 shows a top plan view of the machine; Fig. 4 shows a portion of the cloth-plate of the machine, illustrating in plan the lower clamp-plate of the work-holder, and a part of the mechanism for actuating the same; Fig. 5 shows, in side elevation, a detail illustrating the presser-foot and the upper clamp-plate of the work-holder; Fig. 6 shows in front elevation the parts of Fig. 5; Fig. 7 shows, in top plan, the presser-foot of Fig. 5, the clamp-plate being removed; Fig. 8 is a transverse vertical section on the line 8--8 of Fig. 5; Fig. 9 is a front elevation of the needle-bar driving arm and plate; Fig. 10 is a longitudinal section of Fig. 9, on the line 10--10; and Figs. 10^a to 17, inclusive, illustrate diagrammatically some of the designs and eyelets which may be made by the mechanism of my invention. Fig. 18 is a detail showing the manner in which the connection 52 is made adjustable.

Primarily, I desire it understood that changes may be made in the mechanism herein illustrated, which will enlarge the

scope and change the production of the machine, without departing from my invention or the spirit thereof. For example, the operating cams may be changed or altered as to their action, form, or construction; the working position of actuating parts of the work-holder may be automatically changed; and the mechanism, or a part thereof, may be used in combination with other mechanism for making buttonholes of various kinds.

Throughout this description, I will refer to the "fields" from which the stitches radiate, and by said term I mean to comprehend either the center, or point, from which each stitch radiates, or that space or opening, no matter what its form or shape may be, from which, or relatively to which, the stitches extend outwardly into the body of the material or work.

In the drawings: the frame of the machine is indicated by 1, the same including the usual overhanging arm, cloth-plate and the head. The power shaft 2, as is usual, imparts to the needle-bar 3, its reciprocating movement in the head of the machine by any suitable means, said needle-bar being carried in the needle-bar gate 3*, so as to receive a vibratory movement at an angle to its reciprocating movement. A usual form of switch-cam such as is used in zig-zag or overseaming machines, is attached to the upper shaft of the machine. This switch cam and other parts of usual construction it is not thought necessary to illustrate. A driving arm 4, is in engagement with the said switch-cam by means of a usual switch-cam follower (not shown), which is carried by a stud 5, attached to the upper end of the arm 4, an opening 6, being formed in the arm of the machine to permit said engagement. The driving arm 4, is carried by a shaft 7, journaled in the under side of the overhanging arm and extending transversely thereof from front to rear, see Figs. 1, 2 and 10—and at its rear end is provided with a similar driving arm 8. Each of the arms 4 and 8, is extended on opposite sides of the supporting shaft 7, thus providing means for connecting thereto an adjustable driving-plate, the one 9, being connected to the arm 4, and the one 10, being connected to the arm 8.

The forms of the driving arms 4 and 8 is

not of the essence of my invention; for, it will be clear that the same may be substantially straight, or may be formed on the arc of a circle, and such arcs may have the pivots 5 74 and 75, as their centers. Each of the driving-plates is provided with curved slots 11, one at each end, through which extend adjusting screws 12, for the purpose of fixing said plates to the respective arms in any desired position. Each of the plates 9, and 10, 10 is carried by a support 9^a, pivoted centrally to its driving arm, as at 9^b, thus permitting the adjustments suggested, and the bosses 9^c, hold the plates away from the supports 15 9^a. See Fig. 10.

Each of the driving-plates is provided with a longitudinal, curved slot 13, which are disposed in an arc of a circle about pivots 74 and 75, when the plates are in certain adjustments which will be explained further on in this specification. Shaft 2, is provided with an eccentric 14, which actuates a usual strap 16, pivoted to a bell-crank lever 17, one arm 18, of which is provided with a curved slot 25 19, in which is adjustably secured one end of a link 20, in any suitable manner, and the other end of which is connected to a pawl-actuating arm 21, carrying at its upper end a pivoted pawl 22, which co-operates with the 30 teeth of the ratchet wheel 23, fixed to a transverse shaft 24, journaled in a bracket 25, fixed in any suitable manner to the top of the overhanging arm.

The strap connection 16, comprises two 35 parts, 14^a is a band that completely encircles the eccentric and is retained on the periphery of the same in a usual manner. In the sides of this band is located pins 15^b, (only one of which is shown) and on said pins is 40 pivoted a forked end 16^c of the connection 16, (only one prong of said fork is shown). The pins are of course directly opposite each other, and there is sufficient clearance between the forked end of the part 16 and the 45 band 14^a to permit of the slight lateral movement of the upper end of said part 16 necessary for the free action of the said connection between the eccentric and the bell crank lever 17: This form of connection is not 50 new and applicant makes no claim to the same. Any suitable form of connection may be used between the eccentric and the bell crank lever 17. The shaft 24, has connected thereto at its front end a cam-disk 26, and at 55 its rear end a cam disk 27. These disks 26, and 27, are grooved so as to produce the cam paths 28 and 29, respectively. The cams formed in these disks are what are called heart shaped cams, but as is well known 60 these heart shaped cams may vary greatly in the movement they transmit. In the present form of my invention these cam grooves are so constructed that they run from the point 24* progressively in a direction away

from the axis of the shaft 24 until the point 65 24^a is reached. So it will be understood that they transmit a progressively reciprocating movement of a uniform speed to the parts that are in direct engagement with them. These cams are constructed to stitch 70 or embroider the figures herein illustrated, but it will be clearly understood when these cams and the other parts to be described that they operate are considered, that an unlimited 75 number of different shaped cams may be inserted and used in place of these, and the design of the embroidery or stitching thereby changed accordingly.

Suitably supported at a point in front of the shaft 24, is a stud-shaft 30, carried by a 80 bracket 31, fixed to the arm of the machine, and journaled upon opposite ends of said stud-shaft 30, are the arms 32 and 33, both extending toward the rear end of the machine and the arm 32, carrying a stud 34, 85 which travels in the groove 28, of the disk 26, while the arm 33, carries a stud 35, which travels in the groove 29, of the disk 27. The stud 34, pivotally supports a rod formed in two parts, the part 37, sliding upon the part 36, and being adjustable thereon to any extent desired by means of the thumb-screw 38, passing through a longitudinal slot 39, in the part 37, and being tapped into the part 36. The lower end of the part 37, of the bar, 90 pivotally connects with a two-part pitman, one portion 40, of which slides and is adjustable on the part 41, by means of the clamping loop 42. The pitman connects at 74, with the needle-gate and transmits motion 100 thereto from the driving-plate 9, by means of the stud 43, which forms the pivotal connection between the part 37, of the rod and the part 41, of the pitman, and which stud extends into a shoe 9^x, which slides in the slot 105 13, of said driving-plate 9. The shoe 9^x is constructed in a usual way, and provided with usual means for retaining it in the way or slot 13.

The stud 35, pivotally supports the upper 110 end of a two-part rod, one part 44, sliding in the other part 45, and being adjustable relatively by means of the set-screw 46, passing through a longitudinal slot 47, in the part 45, and tapped into the part 44. At its lower 115 end the part 45, is pivotally connected to the forward end of a link 48, the pivotal stud 49, extending through the part 45, and link 48, and having a shoe operating in the slot 13, of driving-plate 10, in like manner as above described in connection with stud 43, and shoe 9^x. Link 48, at 75, is pivotally connected to the lever 50, fulcrumed at 51, on the arm of the machine, having its other end connected to an adjustable pitman 52, which at its forward end is pivotally connected to the bell-crank lever 53, fulcrumed at 54, to the cloth-plate of the machine. 120 125

The pitman 52 is provided at one end with a right hand thread and at its other end with a left hand thread that have seats in correspondingly threaded bores in end-pieces 52^a and 52^b. This is a usual way of making a pitman adjustable, and the said ends are locked in their threaded seats by usual lock nuts seen in Fig. 2. The piece or bearing 52^a is adapted to embrace in a usual manner a ball carried by the lower end of the lever 50, and the piece 52^b is adapted in a like manner to embrace a ball carried by one arm of the bell crank lever 53.

The arm 55, of the bell-crank is bifurcated 15 and the fork 56, thereof embraces a block 57, pivotally supported on the bottom of the slide-plate 57^x, of the work-holder (see Figs. 1 and 2.) Said slide-plate, supports the lower-clamp-plate 58, of the work-holder and 20 slides in ways 59, supported by the cloth-plate, and such ways confine said slide-plate and clamp-plate to a right-line reciprocation. The slide-plate 57^x, and clamp-plate 58, are connected, so as to move together, by means 25 of the thumb screw 58^x, carried by the clamp-plate and extending through an open-end slot, in the slide-plate 57^x, and the clamp-nut 58', screwing upon the pin 58^x, and engaging the slide-plate. This construction enables 30 the clamp-plate to be removed, or slid back, at will, thereby providing a free passage for the bobbin from the machine. The plate 58, at its forward end, is serrated at 60, and is provided with a needle-aperture 61.

35 The presser-bar 62, supports a foot 63, the horizontal portion of which carries anti-friction rolls 64, running in grooves or ways 65, in the upper clamp-plate 66, of the work-holder. The bottom of the upper clamp-plate 66, is serrated at 67; and the flanges 68, afford a means by which said clamp-plate 66, may be retained upon the presser-foot and also form the groove 65, in which the rolls run and whereby plate 66, is retained from 45 lateral movement on the foot. At its rear end the plate 66, is provided with a lug or extension 69, having an aperture therein in which is set a light spring 70, fixed by a screw 71, to the shank portion of the foot 63. Obviously, when the presser-bar is lowered the plate 66, will clamp the work upon the plate 58, said plates thus securely retaining the work and constituting the work-holder. As 50 the plate 58, is moved the plate 66, will correspondingly move, and the spring 70, will be flexed and thereby caused to exert tension upon the plate 66, sufficient to return it, when it is raised from the work, to its normal position shown in Fig. 5.

55 72, is an aperture provided in the presser-foot for the passage of the needle.

In the operation of the machine the function of the arms 32 and 33 is to keep the studs 34 and 35 in their proper position so

that they will be retained in the cam grooves. 65 These arms are of such length, and the movements transmitted from the cams so limited that the effect of the movement of the studs is, at the stitching point, substantially the same as it would be if the studs were confined 70 to move in a right line only. It is obvious that other means might be used for guiding the ends of the connections 36 and 45 in the cam grooves. For example the well known means of using a slide for transmitting the 75 movement of the cam could be used, but in the present form of my invention the said arms are preferred.

Assuming now that the driving arm 4 has no movement, and that the plates 9 and 10 80 are adjusted as shown in Figs. 1 and 2, it will be seen that the operation of the machine will cause the cam groove 28 to reciprocate vertically the shoe 9^x on which the end of the part 41 is pivoted, and because of the oblique 85 position relative to the vertical of the way 13 the said part 9^x will move laterally as it is reciprocated, and through the connection between it and the needle the said needle will be moved laterally. And as the cam disk 26 90 is revolved from the movement of a ratchet wheel it will be readily understood that this lateral movement of said needle will be progressive, first in one direction and then in an opposite direction. Of course the speed of 95 this progressive reciprocating lateral movement of the needle, may be increased or decreased by adjusting the end of the connection 20 in the way 19 from or towards the pivot of the bell crank lever in which said 100 way is formed.

By referring now to the cam groove 29, and the connection between the same and the work carrier, it will be seen that when the machine is operated as just described, the 105 work carrier will be reciprocated progressively at right angles to the lateral reciprocations of the needle, and it will now be understood that means are present in this machine for producing automatically a relative universal movement between the needle and the work, and as these movements are under the control of two pattern cams it will be seen that an endless number of different designs may be automatically stitched. While the 110 cam grooves are the same in my present selected means for disclosing my invention, it is obvious that their path may be absolutely different, or may vary in any suitable way. And while the ways 13 are uniform it is obvious, that they may be varied, and that their paths may be different relative to each other, and that by making these cam ways, different the pattern stitched will be different or varied.

Assuming now, that the arm 4 is vibrating and the plate 9 is so adjusted that the groove 13 is concentric with the pivot 74 when the

upper end of the said arm is in its extreme position toward the needle, or in the direction of the arrow shown in Fig. 1, the needle will always be in the same position when these parts are moved in this direction so long as the end of the connection 41 is above the pivot of the arm 4. It will be understood that when the parts are so adjusted all of the increase and decrease in the lateral vibration of the needle will be on the right side of a pre-determined point, when the end of said connection is above said pivot, and of course when the said end is below said pivot all of said increase will be on the other side of said pivot. It is to be observed that here are means for increasing outwardly from a central point in one direction the extent of the lateral vibration of the needle, and then decreasing towards said central point the lateral vibration of said needle until said central point is reached again, when no lateral vibration of the needle takes place, and then increasing the said lateral vibration from said central point to the opposite side of the same, and then again decreasing said lateral vibration of said needle until said central point is reached again. Assuming now that the plate 10 is adjusted so that the segment way 13 formed thereby is concentric with the pivot 75 when the upper end of the arm 8 is in its extreme lateral position toward the rear end of the machine, it will be seen that the work carrier will always be in the same position when the end of the connection 48 is directly over the pivot of the arm 8, and that when said connection is moved above said pivot, the work carrier will be vibrated from this central point or position in a direction towards the back of the machine, or from the operator. And as the movement of the end of said connection 48 continues in this direction the vibration of the work carrier will increase from its said central position towards the back of the machine. And of course when the reverse movement takes place this vibratory movement of the work carrier will decrease until the end of the connection 48 is over the pivot of the arm 8. Then as the end of said connection moves below the pivot of said lever 8 the vibratory movement of said work carrier increases on the opposite side of said central position, and then when the reverse movement takes place it decreases towards said central position. It is thus seen that the same movements are produced in the work carrier, under these adjustments, as are produced in the needle, but that the vibrations of the work carrier are at right angles to the vibrations of the needle. Thus it is seen that means are provided here for producing a relative universal vibratory movement between the needle and the work. And

it is to be observed that by the use of this movement stitches may be made to radiate out in any direction from a given center, or around a given field.

In making round eyelets in which the stitches radiate out from a center point such for example as is indicated in Fig. 12, the movements of the needle and the work carrier are as above described. The parts are adjusted to make this eyelet so that as the vibratory movement of the needle decreases, the vibratory movement of the work carrier increases proportionately and outwardly from the common center of action of the needle and the work carrier, and this relative movement takes place during the making of stitches around one quarter of the eyelet, or say from *a* to *b* in Fig. 12. When this point has been reached the end of the connection 41 will be over the pivot of the lever 4, and the end of the connection 48 will be in its extreme position below the pivot of the arm 8. Now the reverse movement commences and the vibratory movement of the work carrier is decreased, and of the needle increased until the end of the connection 48 is over the pivot of the arm 8, and the end of the connection 41 in its extreme position below the pivot of the arm 4, when the stitching will be at *c* in said Fig. 12. And from this point the movements are reversed again until *d* is reached, and then they are again reversed until the starting point *a* has been reached when the eyelet is completed.

The designs indicated in Figs. 12, 13, 14, 15, 16 and 17, are all made by the same mechanism herein illustrated, and without changing the shape of the cams. And other adjustments may be made, and other designs thereby produced. The open fields in the center of designs 13 and 14 are produced by adjusting the plates 9 and 10 laterally so the vibrations of the needle and the work carrier do not extend to the center of the design. The difference in these designs is produced by changing the relative positions of the plates. The designs indicated in Figs. 15 and 16 are produced by adjusting the working position of the ends of the connections 41 and 48 so they work relative more to one side than the other of the pivots of the arms 4 and 8. The working positions of these parts may be adjusted by means of the thumb nut 38, and the thumb nut 46.

Other variation may be made in the designs stitched, by other adjustments in the mechanism. For example the angular position of one of the cams relative to the other may be changed by means of the screws that secure said cams to their shafts, see Fig. 3. And it is obvious that any change in the relative angular positions of these cams will change the shape of the design stitched. It

is thus seen that there is a wide scope in this machine without changing the shape of the cams, but it is to be understood that by changing the shape of said cams there is practically no limit to the number of different designs that may be stitched or embroidered.

It is of course clear from the foregoing description, that the ratchet wheel 23 is the common actuator by means of which the mechanism that acts to vary the extent of the vibrations of the needle, and of the work holder is operated. And it is of course also clear that the cams operated by the said ratchet wheel produce the desired change in the extent of the lateral vibrations of the needle and of the work holder or carrier. It is also understood that the spacing of the stitches around the design is secured by changing the extent of the stroke of the actuating pawl 22.

Figs. 10^a and 11, illustrate two of many designs which may be produced by changing the form of the cam-paths employed in forming the designs of the other figures.

Having thus described my invention what I claim and desire to secure by Letters Patent is:

1. In a sewing machine, a stitch-forming mechanism comprising a needle that reciprocates in the direction of its length, a non-rotative work holder, a vibrating part acting upon one of these elements to produce relative movements between them in one direction, a second vibrating part acting upon one of these elements to produce relative movements between these parts in a direction at right angles to that given by the first-mentioned vibrating part, means for operating the vibrating parts to change the movements of the same to produce relative movements between the needle and work holder radially completely around a given center thereby stitching an eyelet without turning the work.

2. A sewing machine comprising a reciprocating and laterally vibrating needle, a work holder vibrating at right angles to the direction in which said needle vibrates, means for vibrating said needle and work holder, and means for automatically changing the movements of the same to produce relative movements between the needle and work holder radially completely around a given center.

3. A sewing machine comprising a reciprocating and laterally vibrating needle, a reciprocating work holder confined to move in a right line at right angles to the direction in which said needle vibrates, means for vibrating said needle and work holder, and means for automatically changing the movements of the same to produce relative move-

ments between the needle and work holder radially completely around a given center. 65

4. A sewing machine comprising a reciprocating and laterally vibrating needle, a non-rotatable work holder, means for vibrating said work holder in a direction at right angles to the lateral movements of said needle, and means for automatically changing the movements of the needle and work holder to produce relative movements of a uniform extent between the same radially completely around a given center. 75

5. A sewing machine comprising a reciprocating and laterally moving needle, a work holder that reciprocates at right angles to the direction in which said needle moves laterally, and a ratchet operated mechanism for changing relatively the lateral movements of said needle and the reciprocating movements of said work holder to produce relative movements between the same radially completely around a given center. 85

6. A sewing machine comprising a reciprocating and laterally vibrating needle, a work holder that reciprocates at right angles to the direction in which said needle vibrates, and means for changing relatively the movements of said needle and work holder to produce relative movements between the same of varying extent radially completely around a given center. 90

7. A sewing machine comprising a reciprocating and laterally vibrating needle, a work holder that vibrates at right angles to the direction in which said needle vibrates, means for changing relatively the vibratory movements of said needle and work holder to produce relative movements between the same radially completely around a given center, and means for changing laterally the working position of one of said elements. 95

8. A sewing machine comprising a reciprocating and laterally vibrating needle, a work holder that vibrates at right angles to the direction in which said needle vibrates, means for changing relatively the vibratory movements of said needle and work holder to produce relative movements between the same radially completely around a given center, and means for changing laterally the working position of said needle and work holder. 105

9. In a sewing machine, a needle that reciprocates in the direction of its length, a work holder, an oscillating lever that is pivoted intermediate its ends, an auxiliary plate adjustably mounted on said lever and a sliding part mounted on said plate, a connection between said sliding part and the needle, a second oscillating lever that is pivoted intermediate its ends, an auxiliary plate mounted adjustably on said second oscillating lever, a sliding part mounted on said

plate, a connection between said sliding part and the work holder, and a ratchet operated mechanism for operating said sliding parts to produce relative movements between the 5 needle and the work holder radially completely around a given center.

10. A sewing machine comprising a reciprocating and laterally vibrating needle, a work holder vibrating at right angles to the 10 direction in which said needle vibrates, means for vibrating said needle and work holder; and means for automatically changing the movements of same to produce rela-

tive movements between the needle and work holder radially completely around a 15 given center comprising two cams one of which controls the action of the needle vibrating means and the other the action of the work holder vibrating means.

In testimony whereof I have hereunto 20 signed my name in the presence of two subscribing witnesses.
